COMBINED CLOCK RADIO AND LAMP

Hachiro Masuda, Lodi, and Morris J. Feldman, North Caldwell, N.J., assignors to York Radio Corp., South Hackensack, N.J.

Filed Aug. 6, 1970, Ser. No. 24,342

Term of patent 14 years

Int. Cl. D26—05; D14—03; D10—01
U.S. Cl. D42—7

FIG. 1 is a perspective view of a combined clock radio and lamp showing our new design;

FIG. 2 is a right side elevational view;

FIG. 3 is a left side elevational view;

FIG. 4 is a top plan view with the lamp member removed for ease of illustration;

FIG. 5 is a bottom plan view;

FIG. 6 is a front elevational view; and

FIG. 7 is a rear elevational view.

We claim:

The ornamental design for a combined clock radio and lamp, as shown and described.
